No. 875,840.

PATENTED JAN. 7, 1908.

C. A. OLSEN.
IRONING BOARD.
APPLICATION FILED JAN. 28, 1907.

UNITED STATES PATENT OFFICE.

CHARLES A. OLSEN, OF SHERMAN, SOUTH DAKOTA.

IRONING-BOARD.

No. 875,840.

Specification of Letters Patent.

Patented Jan. 7, 1908.

Application filed January 28, 1907. Serial No. 354,558.

To all whom it may concern:

Be it known that I, CHARLES A. OLSEN, residing at Sherman, in the county of Minnehaha and State of South Dakota, have invented certain new and useful Improvements in Ironing-Boards, of which the following is a specification.

My invention relates to certain new and useful improvements in ironing boards and it primarily has for its object to provide an ironing board of a very simple and effective construction, which can be easily and cheaply manufactured and which can be readily attached to the wall or removed therefrom, as desired.

In its more detail nature, my invention comprises an improved means for detachably securing the board to the wall which means include a hinge joint of such construction that the board carried hinge member may be formed also into a holder for a sheet of asbestos, or other fire-proof material, to act as an iron-stand, the construction of said hinge being such that it coöperates to hold the asbestos in place.

Again, my invention includes certain novel construction, combination and arrangement of parts, all of which will be first described in detail, and then be specifically pointed out in the appended claims, reference being had to the accompanying drawings, in which:—

Figure 1, is a perspective view of my invention in use. Fig. 2, is a perspective view of the board detached. Fig. 3, is a central vertical longitudinal section of the parts shown in Fig. 1. Fig. 4, is a transverse section on the line 4—4 of Fig. 3. Fig. 5, is a detail perspective view of the hinge member detached. Fig. 6, is a similar view of the adjustable leg detached.

Referring now to the accompanying drawings in which like letters and numerals of reference indicate like parts in all of the figures, 1 designates the wall of a room to which a pair of bracket members 2—2 are secured, the bracket members being spaced apart a sufficient distance to receive the ironing board 5 hereinafter again referred to. Each bracket member comprises ears 2^a apertured to receive the securing screws 2^b, and a wing portion 2^c provided with a series of apertures

2^d to receive the pivot stud and bolt of the ironing board 5.

3 designates the board carried hinge member, which in practice, is preferably formed of sheet metal, and comprises the rear board engaging portion 3^a, which merges with a circularly bent pivot bolt receiving portion 3^b, as indicated. The sheet metal hinge member 3 is also bent from the member 3^b, at right angles to the portion 3^a as at 3^c, thus forming a right angled socket for the receipt of the rear end of the board 5, and forming a horizontal flange 3^e and a vertical flange 3^a, as it were, when the board is in its normal position, as indicated in Fig. 1. The flanges 3^a and 3^e are each provided with a series of apertures 3^d through which the securing screws 3^e are passed into the ironing board 5. The ironing board 5, it should be stated, is provided with a rear brace 5^a to abut the flange 3^a of the hinge member and to which the flange 3^a is also secured.

Within the bolt receiving portion 3^b of the hinge member 3 and at one side thereof a fixedly held stud 3^g is mounted and the stud 3^g is adapted to enter the apertures of one of the bracket members 2, hereinbefore referred to. A sliding bolt 3^h is also held within the portion 3^b of the hinge member 3 which bolt is provided with a finger engaging projection 3^k which projects through a slot 3^m in the portion 3^b of the hinge member, the slot 3^m being of the nature of a bayonet slot, as shown, so that by a slight rotation of the bolt 3^h it can be locked in its projected position. The projected end of the bolt 3^h is adapted to enter the apertures of the other bracket member 2 and thus form with the fixed stud 3^g and the bracket members a hinge connection between the board 5 and the wall 1.

The hinge member 3 has its flange 3^e provided with a projecting portion 3^r which has an up-turned edge 3^s and is adapted to be clamped over and abut the pad 4 of asbestos or other suitable material, which pad 4 projects tightly up into the fold 3^x between the flange 3^e and the bolt receiving portion 3^b of the hinge member 3, see Fig. 1. The pad 4 is thus adapted to be used as an iron-rest and by virtue of its being adjusted close

against the wall end of the board it is out of the way of the user and will not interfere with the free use of the board.

The ironing board 5 is provided with a second brace 5^b near its forward portion to the under-side of which a metallic bracket member 6, preferably constructed of sheet metal, is secured, by a screw 6^a and is provided with apertured ears 6^b through the apertures of which a bolt 7 may be passed. Pivotally mounted between the ears 6^b is a metallic channeled member 8 which is preferably formed of sheet metal bent into substantially U-shape in cross section to form a channel in which a leg 8^a is held and the leg 8^a is held in place by a bolt 9 which passes through an elongated slot 8^b in the member 8^a, whereby the leg 8^a may be extended with respect to the member 8. For purposes readily understood, the bolt 9 may be provided with a washer 9^a to coöperate with its head and engage the leg 8^a, and secured in place by a nut 9^b, as shown. The lower end of the leg 8^a is preferably V-shaped as at 8^c to fit within the angle made between the floor and the wall.

From the foregoing, it will be seen that I have provided a very simple and effective construction of ironing board which can be easily and cheaply manufactured and which can be quickly attached to or detached from its wall support, and which may be also adjusted on its wall brackets to bring the same at different heights from the floor, it being understood that the leg 8^a is drawn out or shortened to correspond to the height of the board from the floor as may be necessary.

From the foregoing description, taken in connection with the accompanying drawings it is thought the complete construction, operation and many advantages of my invention will be readily understood by those skilled in the art to which it appertains and I desire to say that many slight changes in the detailed arrangement of parts may be made without departing from the invention.

What I claim is:—

1. An apparatus of the class described, comprising the combination with a fixed support, bracket members secured thereto, of an ironing board, said ironing board having a forward brace, a bracket member fixedly secured thereto, a leg carrying member pivotally secured to said bracket member, a leg adjustably secured to said leg carrying member, a sheet metal hinge member secured to the end of said ironing board, said sheet metal hinge member including an integrally formed hinge bolt and stud receiving portion, a fixed stud held in said receiving portion for coöperating with apertures in one of said brackets, an endwise shiftable bolt held in

in said receiving portion of the hinge member and adapted to be projected into an aperture in the other bracket member, and means for locking said bolt in its projected position.

2. An apparatus of the class described comprising the combination with a fixed support, bracket members secured thereto, an ironing board having a forward brace, a bracket member fixedly secured thereto, a leg carrying member secured to said bracket member, a leg adjustably secured to said leg carrying member, a sheet metal hinge member secured to the end of said ironing board, said sheet metal hinge member including an integrally formed hinge bolt and stud receiving portion, a fixed stud held in said receiving portion for coöperating with apertures in one of said brackets, an endwise shiftable bolt held in said receiving portion of the hinge member and adapted to be projected into an aperture in the other bracket member, means for locking said bolt in its projected position, said board carried hinge member also including an up-turned and clenched over projecting portion adapted to hold a pad, substantially as shown and for the purposes described.

3. In an ironing table, a fixed support, bracket members secured thereto and having a series of apertures, an ironing board, and adjustable leg secured beneath the same, a sheet metal hinge member secured to said ironing board at one end and comprising a flange for engaging the rear edge of the board, a tubular bolt receiving portion and a second flange projected at right angles to the first flange and adapted to engage the top of the board, a fixed stud held in said tubular bolt receiving portion at one end and projected beyond the same, for entering one of the bracket apertures, an endwise slideable bolt held in said tubular bolt receiving portion, adapted to be projected into an aperture of the other bracket member, said bolt having a finger engaging projection, and said tubular bolt receiving portion having a longitudinal slot to coöperate with said finger engaging projection, substantially as shown and described.

4. In an ironing board, a fixed support, bracket members secured thereto and having a series of apertures, an ironing board, an adjustable leg secured beneath the same, a sheet metal hinge member secured to said ironing board at one end and comprising a flange for engaging the rear edge of the board, a tubular bolt receiving portion and a second flange projected at right angles to the first flange and adapted to engage the top of the board, a fixed stud held in said tubular bolt receiving portion at one end and pro-

jected beyond the same, for entering one of the bracket apertures, an endwise slidable bolt held in said tubular bolt receiving portion and adapted to be projected into an aperture of the other bracket, said bolt having a finger engaging projection, said tubular bolt receiving portion having a longitudinal slot to coöperate with said finger engaging projection, and said second flange having a projecting portion with an up-turned and clenched over edge adapted for holding the pad, substantially as shown and for the purposes described.

CHARLES A. OLSEN.
